MECHANICAL HAND FOR ARTIFICIAL ARMS

Eddie Craig Jarrett, Fillmore, Calif.

Application March 30, 1943, Serial No. 481,167

5 Claims. (Cl. 3—12)

My invention relates to a mechanical hand for an artificial arm of which there are a variety of such implements heretofore used and known. My invention being an improvement for better service and use than any other appliances or mechanisms heretofore used or known by me.

My mechanical hand is operated by the wearer in the same manner as are other mechanisms of this type, by having a cord or suitable cable extending from the hand up the sleeve of the natural arm and over and around the shoulder blades whereby on shrugging or moving the shoulders a tension is produced on the cable which opens the fingers of the mechanical hand, while a spring mechanism in the hand itself makes the closure of the fingers.

My mechanical hand is applied to the stump of the natural arm in a similar manner as are other similar device by being held rotatively in the end of a suitable sleeve of leather or other material which is laced and secured in any suitable manner to the stump end of the arm remaining of natural character.

My invention relates to details of constructions which add to the efficiency and convenience in the use of a mechanical hand.

An object of my invention is to provide a simple and inexpensive construction which can be made at small expense and yet arrive at efficiency of service not heretofore obtained by other devices or appliances known.

A further object of the invention is to provide shapes of the fingers for a mechanical hand which will hold with more security and afford more general service and convenience in the use of this hand than has heretofore been accomplished, insofar as I have been informed.

Other objects of the invention will appear by the descriptions and the claims hereof.

Reference will be had to the accompanying drawing in which:

Fig. 1 is a perspective view of my mechanical hand mounted in the end of the holding sleeve which is mounted on the front end of the stump of a natural arm.

Fig. 2 is a top plan view of my invention.

Fig. 3 is a side elevation of what is shown in Fig. 1 with parts broken away for inspection and for clearness of illustration.

Fig. 4 is a section on line 4—4 of Fig. 3.

Fig. 5 is a perspective view of detailed parts looking in the direction of an arrow small a of Fig. 3.

Fig. 6 is a perspective view of parts shown at the right of Figs. 2 and 3.

In the drawing 2 indicates the mechanical sleeve which is attached in any suitable manner to the stump end of a natural arm. In the outer end of this sleeve there is a circular socket, not indicated in the drawing as it is of common general construction and is not generally shown herein. My invention is secured to this socket 10 like other mechanical hands by means of a circular disk 3 of any suitable form. The point being that this mounting in the sleeve 2 provides that the disk 3 may be rotated therein in the end of said sleeve 2 through any suitable arc desired for service of a mechanical hand.

The actions produced by the wearer are brought about by an operating cord or cable 4 which extends up the sleeve of the wearer and up and around the shoulders of the wearer in the same manner as is common practice with other devices of this character whereby the movements of the shoulders produce a tension on the operating cord 4 which results in opening the finger bars 5 of the mechanical hand through the mechanism hereinafter described, tension of the cable or cord 4 pulls the tube 8 to the right, the tube 8 in turn puts tension on the tie rods 20, thereby causing the fingers 5 to open, see Figs. 2 and 3, and on the release of the tension of the cord, spring means 10 in the mechanical hand close the fingers of the hand on to any object which may be grasped by the mechanical hand.

35 My invention is provided with fingers bars 5 which are hinged by pins 6 to a circular supporting longitudinal bar 7 which extends back through a movable tube 8 and on to the right end of the bar 7 there is screwed the nut 9 which abuts against the aforementioned circular disk 3.

40 A spring 10 is mounted over the longitudinal bar 7 and abuts against the circular disk 3 and the other end of the spring 10 abuts against the end of the movable tube 8 with an extending 45 pressure to push the tube 8 asunder from the disk 3. On this end of the tube 8 which abuts against the spring 10 there is screwed a flange nut 11.

The spring 10 is covered by a short piece of a 50 tube 12 performing no other function than a coverage for the spring 10 and a limiting movement to the right of the movable tube 8.

Astride the tube 8 there is a plate 13 loosely mounted thereon, one end of which is turned over at 14 clasping a stirrup 15, the ends of which

are screwed into perforations in the disk 3. On the other side of the plate 13 there is a projection 16 into which the operating cord or cable 4 is secured.

The movable tube 8, at the left end thereof, has mounted thereon a block 17, see Fig. 5, which is held in place by collars 18, one on each side, and which allow the block 17 to revolve on the end of the movable tube 8. This block 17 is provided with horizontal flanges 19 at right angles to the main face of the block 17.

Tie rods 20 have their ends turned over and seated into the flanges 19 of block 17. The tie rods 20 have their other ends 21 hinged into apertures in the outward portions of the fingers bars 5.

Thus when the cable 4 is stressed and moved in the direction of the arrow 22, see Fig. 2, the spring 10 is compressed by the movement of the plate 13 from the full line position shown in Fig. 2 to the dotted lines in said figure. This results in moving the block 17 to the right along the tube 8 and this movement results in opening the fingers bars 5 from the full line positions to the dotted lines, as shown in Fig. 2, thus opening the finger bars 5 which permit the entrance of anything which is desired to be grasped by the mechanical hand as and when actuated through the means of the cable 4 as earlier described herein.

The fingers bars 5 are provided with hook shaped ends 23 on which there are provided circular notches 24 adaptable for grasping any small articles. The hooked shaped ends 23 enable the mechanical hand to hook on to anything which may be desired which may be engaged by such a hook form as is indicated in the drawing. Notches 25 in the vertical side of the fingers bars 5 provide means for grasping securely any small articles such as pencil 26, as is shown in Fig. 1.

In inner edges 27 of the fingers bars 5 are milled for roughening purposes with a series of criss-cross small notches or serrations which assist in holding articles firmly.

The forms and constructions of the parts are of simple shapes and are adapted to be made with relatively few special tools and thus bring down the costs which will permit the furnishing of mechanical hands at little expense to those who most need them, for as a matter of fact, most of the persons who require articles of this class are in the lower earning brackets.

The mechanisms of this mechanical hand provide a greater variety of uses and are more firm in their grasp upon anything to which it is applied to with more general efficiency than any other artificial hand or mechanical device for use as a hand.

The finger bars 5 are provided with parallel companion sides which contact each other substantially their entire service length. This widens the service for firmly grasping varying shaped objects.

I have shown herein a round bar 7 with a flattened end as the central supporting member for the mechanisms of the hand, together with a movable member in the form of a tube sliding over the longitudinal round bar. In place of this tube I might make a companion bar or two companion bars, not necessarily tubular, which I would mount alongside the longitudinal bar 7 for the movable member which functions in the place of the tube 8, as shown in the drawing, but I prefer to use the tube.

What I claim is:

1. In a hand of the class described, a circular disk adapted to be fitted into a supporting sleeve

of the type which may be fastened to the stump end of a natural arm, a circular bar extending through the said disk from the outside of the said sleeve and the end of the said circular bar is provided with a fastening means in the form of a nut screwed thereon and the like, a coil spring mounted on the said bar and abutting against the said circular disk the opposite end of said spring abutting against a tube which tube encloses the said circular bar, a flange nut on the end of said tube adjacent to the said spring, a covering tube mounted over the said coil spring and sliding on said flange nut and extending in contact with the said disk, a plate mounted on the end of said tube adjacent to the said flange nut and adapted to be rocked in angular direction on said tube, a stirrup hinged to the said plate at one side thereof and said stirrup secured into the aforementioned circular disk, a projection on said plate opposite the said stirrup, a cable connected to the said projection, said cable extending up and around the shoulders of the wearer of the hand whereby the hand is operated in functioning, collars fastened on to the outer end of the said tube, a flat block mounted on and between the said collars, said block having flanges turned on its body on each side thereof to a horizontal position, tie rods having their ends turned over and hinged in the said flanges, the said circular bar at its outer end extending outside of the said tube and having its ends flattened, finger bars hinged into the said flattened end of the said circular bar, the aforementioned tie rods having their outer ends turned over and hinged into the said finger bars, said finger bars having milled serrated edges on their sides adjacent to each other and the ends of said finger bars turned over into a hooked shape, curved notches opposite each other on the vertical inside edges of said finger bars forming an aperture adapted to hold an article such as a pencil and the like, a set of curved notches extending horizontally through the body of the said hooked over ends of the said finger bars for the purpose of holding pencils and the like.

2. In a hand of the class described, a longitudinal bar having a flattened outer end, finger bars hinged into the said flattened end of the said bar and extending outwardly from the said bar, a tube into which the said bar extends rearwardly, a block mounted on the outer end of said tube and adapted to be revolved thereon, horizontal flanges on the transverse sides of said block, tie rods hinged into the said flanges of said block and extending outwardly from said block, said tie rods hinged into the body portion of said finger bars; in combination with spring means for moving the said tube outwardly along the said bar which is located within the said tube together with manually operating means for moving the said tube inwardly over the said bar.

3. In a hand of the class described, a longitudinal bar having a flattened outer end, finger bars hinged into the said flattened end of the said bar and extending outwardly from the said bar, a tube into which said bar extends rearwardly, a block mounted on the outer end of said tube and adapted to be revolved thereon, horizontal flanges on the transverse sides of said block and extending outwardly from said block, tie rods hinged into said flanges, said tie rods hinged into the body portion of said finger bars, said finger bars hinged to the said longitudinal bar having their main body portions of their

companion sides parallel to each other and roughened, together with vertical notches transversely of their parallel sides, the ends of said finger bars curved over in hook form, horizontal notches in the companion sides of said hooked ends; in combination with spring means for moving the said tube outwardly along the said bar which is located within the said tube together with manually operated means for moving the said tube inwardly over the said bar.

4. In a hand of the class described, a longitudinal bar forming a supporting member for the hand, said bar fixed into a disk, said disk mounted in a sleeve adapted to be fixed to the stub arm of a person, a movable member mounted on and along the said longitudinal bar and adapted to slide thereon, a spring mounted on said longitudinal bar and adapted to contact the said movable member and press said member outwardly on said longitudinal bar, manually operative means connected to said movable member for withdrawing said movable member compressing said spring, finger bars hinged together on the outer end of said longitudinal bar and extending outwardly therefrom, a block mounted on the outer end of said movable member, said block provided with two horizontal flanges oppositely opposed transversely of said block, tie rods hinged to the said flanges of said block and extending outwardly beyond the ends of said longitudinal bar and movable member, said tie

rods hinged into the body portions of said finger bars.

5. In a hand of the class described, a sleeve adapted to be attached to an arm of a person, a socket in the end of said sleeve, a disk mounted in the said socket, a longitudinal supporting bar having its inner end fixed into the said disk, a tubular movable member mounted over said longitudinal bar, a spring mounted over the inner 10 end of said longitudinal bar, said spring abutting against said disk and with its other end abutting against the inner end of said tubular movable member and adapted to press the tubular member away from the said disk, a plate mounted on the inner end of said tubular member and adapted to engage and push said tubular member against the said spring, a stirrup fixed into the said disk and extending forward and hinged to one side of said plate, a projection on the other 20 side of said plate opposite the said stirrup, an operating cord connected to the said projection of said plate; in combination with suitable finger bars hinged to the outer end of said longitudinal bar, said finger bars extending forwardly from 25 the end of said longitudinal bar, suitable connecting rods hinged into said finger bars and extending rearward of said bars and suitably connected to and be moved by said tubular member.
